UNITED STATES PATENT OFFICE.

HENRY KOCOUREK, OF CHICAGO, ILLINOIS, ASSIGNOR, BY DIRECT AND MESNE ASSIGNMENTS, TO CHICAGO FLEXIBLE SHAFT COMPANY, OF CHICAGO, ILLINOIS, A CORPORATION OF ILLINOIS.

ANIMAL SHEARS.

Application filed May 14, 1920. Serial No. 381,335.

To all whom it may concern:

Be it known that I, HENRY KOCOUREK, a citizen of the United States, and a resident of the city of Chicago, in the county of Cook and the State of Illinois, have invented certain new and useful Improvements in Animal Shears, of which the following is a specification, reference being had to the accompanying drawings, forming a part there-
of.

This invention relates to animal shears and consists of means designed to insure more accurate alignment of the comb and cutter than has been possible in previous constructions. These improvements comprise the features of invention described and shown in the drawing as indicated in the claim:

In the drawings:

20 Figure 1 is a plan view of a clipper head embodying this invention with parts broken away to disclose certain features of construction.

25 Figure 2 is a side view thereof.

Figure 3 is a section at the line, 3—3, on Figure 2.

Figure 4 is an inverted plan view of a comb element.

30 Figure 5 is an inverted plan view of the frame member with other parts removed.

Figure 6 is a diagrammatic view on an enlarged scale of the two cutting elements.

35 The type of clipper with which this invention is concerned consists of a frame member, 1, provided with means for mounting a comb, 2, relatively stationary therewith, and a cutter, 3, mounted for oscillation, interposed between the frame and the comb. A cross-head, 4, attached to, or integral with the cutter is provided thereon for engaging the crank roller, 5, for imparting the necessary motion thereto, causing the cutter to travel over the comb, with which it contacts.

40 A spring tensioned bolt, 6, acts to hold the shearing elements, 2 and 3, together, and also against the boss, 7, and the guide ribs, 8, 8, on the frame, 1.

45 The structure thus far described is of familiar type and it will be noticed that the shearing elements are held in position relative to each other by means of the guide ribs, 8, 8, engaging the cutter, 3, in a groove, 3^a, therein, while the lugs, 9, 9, position the comb, 2. Both positioning devices, 8, 8, and

9, 9, are integral with the frame, 1, and 55 the shearing elements depend, for their proper action upon the accuracy with which these devices are located with respect to each other.

50 In the more common type of clipper, the comb, 2, is apertured at 10, 10, for the reception of circular lugs and it has been found by experience that in machining lugs of that shape, even with the greatest of care, they are frequently found to be more or less out of alignment, with the result that the teeth of the cutter, 3, at the limit of the working stroke thereof in one direction or the other will not properly register with the teeth of the comb member, 2.

55 The diagram in Figure 6 shows in full lines the position of the teeth when the positioning lugs are of circular form and by faulty manufacture have been formed too far to one side; and the dotted lines in the same figure indicate the result when the lugs are not in parallelism with the ribs, 8. In either case, it is evident that in moving the implement forward, the sharp angle formed between the cutter teeth and the comb teeth which they fail to fully overlap at the end of their stroke would tend to pull the hair caught in the bight at the intersection of the cutting edges, and the hair just beyond them would not be cut at all.

60 To avoid these defects the lugs, 9, are made rectangular in cross section as seen in plan, and disposed parallel to the ribs, 8; their relative position and form is shown in Figure 5. In machining the lugs and ribs 75 80 85 90 95 100 105 90 the cutting or milling tool should be made of such form and shape as would "face" all of the surface on that side of the frame member in one operation, leaving upstanding and sharply defined the members, 7, 8 and 9, which will of course insure their parallelism. If at the same time the frame, 1, be mounted in a jig which carries it by engagement with the journal bearing, 11, of the operating shaft, 12, the lugs, 9, will thus be automatically formed in correct relation to the shaft, both as to their surfaces which extend parallel to the shaft axis and those transverse thereto.

The apertures, 10, in the comb, 2, are shaped to receive the rectangular lugs which are of less thickness than the ordinary circular ones, so that the comb, primarily in-

tended for use with clipper-head frames having rectangular lugs, may also be used with those having circular ones, if the apertures be provided as shown with notches in the 5 form of arcs cut out on each side to accommodate the said circular bosses. This expedient is merely for the benefit of users having need of repair combs to fit old style frames.

10 I claim:

In a clipper comprising a frame, in combination therewith a reciprocating toothed cutter guided for rectilinear movement thereon; a fixed comb with its teeth yieldingly 15 held in contact with the teeth of the cutter,

said frame having aligned parallelogrammatic guide ribs for the cutter and aligned parallelogrammatic positioning lugs for the comb formed integrally with said frame and projecting from the bottom thereof, said rib 20 being parallel to said lugs; whereby said ribs and lugs may be faced or machined simultaneously by tooling means mounted in fixed relation to each other, thus insuring parallelism and invariable spacing. 25

In testimony whereof, I have hereunto set my hand at Chicago, Illinois, this 28th day of April, 1920.

HENRY KOCOUREK.
